CLAIM

We claim the ornamental design for a one-piece spare wheel and tire mount for a hitch receiver, as shown and described.

DESCRIPTION

FIG. 1 is a partial perspective view of a one-piece spare wheel and tire mount for a hitch receiver in an environment of use according to our new design.

FIG. 2 is a top-rear perspective view of the one-piece spare wheel and tire mount for a hitch receiver according to our new design.

FIG. 3 is a bottom-front perspective view thereof.

FIG. 4 is a left-side elevation view thereof.

FIG. 5 is a right-side elevation view thereof.

FIG. 6 is a front elevation view thereof.

FIG. 7 is a rear elevation view thereof.

FIG. 8 is a bottom plan view thereof; and,

FIG. 9 is a top plan view thereof.

Dot-dash broken lines shown in FIG. 1 illustrate the periphery of the drawing view and form no part of the claimed design. Further broken lines illustrate the utility task vehicle, a spare wheel and tire, and portions of the one-piece spare wheel and tire mount for a hitch receiver that form no part of the claimed design.
